HOWARD C. CURTISS, OF NORWOOD, OHIO, ASSIGNOR TO THE AMERICAN LAUNDRY MACHINERY COMPANY, OF CINCINNATI, OHIO, A CORPORATION OF OHIO.

IRONING MACHINE.

Application filed August 3, 1923. Serial No. 655,427.

This invention relates to flat work ironers for use in pressing materials, such as laundry work, the invention relating more particularly to means for causing the machine to operate, if desired, as a floating roll machine wherein the ironing rolls are caused to float between springs and bear upon the work with just the desired degree of pressure.

The customary ironing machine of this general type, which is referred to herein as the "standard", usually includes an ironing bed having concave grooves for receiving padded ironing rolls. These rolls are usually mounted in two side pressure bars so that they may be moved down as a gang, with yielding ironing pressure upon the bed. In these machines, the downward pressure applied to the ironing bed or to work thereon not only includes the spring pressure but also the weight of the rolls, with the result that materials being pressed do not receive the proper finish. In some cases buttons are broken and rough dry spots occur around the buttons and adjacent the edges or thickened portions of seams. These undesirable results are due, to a great extent, to an improper degree of ironing pressure and to the fact that after the machine has been working for a short time, the padding becomes hard and loses its life so that it does not permit the thickened portions of the garment to become properly imbedded therein and thereby do away with these rough dry spots, it being obvious that if the garment with its thickened portions would imbed itself into the padding of the roll, the roll would follow the uneven surface of the garment and produce a perfect finish.

In order to overcome the foregoing difficulties and to increase the life of the padding, floating roll types of ironing machines have been devised, said machines being provided below the ironing roll with springs or other means for relieving the downward pressure of the ironing rolls to such an extent that they bear with the desired or ideal ironing effect upon the work. In one instance, the springs were arranged below the bearings of the rolls and a stationary part of the frame so located that when all spring pressure was removed from above, the rolls would be in contact with the ironing face of the bed at zero pres-

sure. Thereafter, the desired ironing pressure was created from above, such as by an upper spring. This type of mechanism is more or less difficult to adjust and does not afford an effective opportunity for indicating the condition of the padding and the ironing pressure being applied, factors which the operator should be aware of at all times and especially during the operation of the machine.

With the foregoing in mind, the object of the present invention is to provide an improved flat work ironer in which the ironing rolls are movable as a gang into and out of operative relation with the bed, said rolls being so mounted and arranged that they may be readily and accurately adjusted or positioned to produce the desired ironing effect; and in which ironer suitable mechanism is provided for indicating the condition of the padding of the ironing rolls and the amount of ironing pressure effective upon the work.

Further features of the invention will be brought out in the following description, drawings and claims.

Referring to the drawings, which illustrate one suitable embodiment of my invention, Fig. 1 is a side elevation of a flat work ironing machine constructed according to my invention, parts being broken away to expose interior parts; Fig. 2 is a sectional view of the controlling device for converting the machine from the floating roll type to the standard stype; Fig. 3 is an enlarged sectional view of the mechanism associated about the bearings of each of the several rolls; Fig. 4 is a similar view with some of the parts shown in elevation; Fig. 5 is a horizontal section upon the line 5—5, Fig. 3; Fig. 6 is a horizontal section upon the line 6—6, Fig. 4; and Fig. 7 is a vertical section on the line 7—7, Fig. 4.

In the specific embodiment shown in the drawings, 1 represents the main frame of the usual flat work ironer type, and provided with inclined upper rails 2, which are provided on their upper edges with stops 3 and bearing block guides 4 for the several ironing rolls. These bearing block guides are rectangular in form and open out at the top edge so that the bearing blocks may be readily inserted therein, as will later appear. In the bottom of each of these guides is a suitable pad or

projection 5 for a purpose which will later appear. The main frame 1 is provided with parallel perch rails 6, one on each side, adapted to extend in parallelism with the rails 2, as 5 clearly indicated in Fig. 1.

Arranged upon the perches 6 is a heated ironing member or bed 7, provided with concave ironing faces 8. These concave ironing faces are directly below the bearing 10 guides 4, so that when the ironing rolls are supported therein their peripheries engage in the cavities of the ironing member. Slidably mounted in each of the bearing guides 4 is a bearing block 9, each of which is provided 15 on its lower side with a pad or projection 10. Rotatably mounted in each pair of opposed bearing blocks 9 are trunnions 11 supporting an ironing roll 12, provided with padding 13 built up in the usual 20 manner by winding upon said roll a layer of felt or other similar material. There are usually two convolutions of felt upon the roll and a cover cloth is applied to the padding by laying the edge of the cover cloth 25 under the end of the outer padding layer and then winding the cloth about the padding thus formed.

Above each end of the ironing rolls 12 is a pressure bar 14, U-shape in cross section, 30 as shown in Fig. 7, which bar carries the resilient roll supporting mechanism and the indicating mechanism, as will later appear. As the mechanism for each end of each roll is identical, a description of one will suffice for 35 all.

Extending upwardly from each bearing block 9 is a threaded stud 15, on the upper end of which is threaded a push rod 16 which extends upwardly through the channel of 40 the pressure bar 14 and into an upper housing 17 formed integral therewith. The top portion 18 of this housing is threaded to receive a hollow pressure screw 19, which in turn receives the upper reduced end 20 of the 45 push rod 16. Said pressure screw 19 is provided with an operating hand wheel 21, and with a lock nut 22 for holding the screw in any adjusted position. The reduction in the size of the push rod provides a shoulder 24 50 within the pressure bar 14, as clearly shown in Fig. 3, against which shoulder seats a thrust collar 25, pinned or otherwise suitably secured to rod portion 20 and adapted to take the lower thrust of an ironing pressure spring 26. The upper end of said 55 spring engages a thrust collar 27, keyed to rod portion 20, as at 28, and adapted to be engaged by pressure screw 19. The upper and lower thrust collars 27, 25 are respectively provided with laterally extending ears 29, 30 for attachment to the pressure and padding indicating mechanism, as will appear. It will thus be seen that pressure exerted upon the spring 26 will be transmitted 60 through the fixed collar 25 to the ironing roll. 65

The foregoing mechanism, while different in many details from the standard type of spring pressure mechanism, is nevertheless substantially similar in its action to the usual spring mechanism utilized in the standard 70 type of flat work ironer.

Slidably mounted upon the main portion of the push rod 16 below the shoulder 24 is another thrust collar 31 held from rotation on said rod by a key 32. This thrust collar 75 31 is engaged by the upper end of a pressure relieving spring 33 surrounding the main portion of the push rod and engaging at its lower end an adjusting nut 34 loosely surrounding the push rod and threaded in a transversely extending web 23 of the pressure bar 14, a set screw 35 being provided to hold said nut in any adjusted position. By adjusting this nut 34, the tension of spring 33 may be varied to support the weight of 80 the ironing roll or to resist the resilient downward pressure of the upper spring 26 upon the roll sufficiently to give the desired ironing effect.

In order to enable the operator to relieve the machine of the action of the lower or far springs 33 and operate the machine in the standard way, each spring pressure mechanism is provided with means for rendering the lower spring 33 ineffective. This mechanism comprises in each instance a pair of levers 36 straddling the corresponding upper or near spring 26 and engaging extensions 37 projecting laterally from the thrust collar 31, as clearly shown in Fig. 6. These levers 36 are preferably formed integral with the hub 38 which is secured to a shaft 39 mounted in suitable bearings in the pressure bar 14, said shaft extending inwardly to one side of the pressure bar where it is provided with an operating lever 40. Said lever is provided with a bifurcated end adapted to be engaged by a collar 41 arranged upon a longitudinally extending control rod 42, suitably mounted in bearings 43 in the frame of the machine. On the front end of each control rod 42, (it being understood that there is one control rod for each end of the ironing rolls), is threaded an operating handle 44 for longitudinally moving said rod, rotary movement thereof being prevented by the key 45, as clearly shown in Fig. 2. To prevent accidental disengagement of rod 42 and handle 44, said rod is provided on its outer end with a stop plate 46 which normally engages the inner wall of recess 47 in the central portion of the handle. When it is desired to hold the rod in its outer position, handle 44 is screwed inwardly on rod 42 until stop plate 46 of the rod engages stop plate 48 of the handle, the latter stop plate covering recess 47 of the handle. It is obvious that when the rod 42 is moved outwardly or to the left, as shown in Fig. 1, the levers 36 will depress the several lower springs 33 and relieve all their upward pressure, or in other 90 95 100 105 110 115 120 125 130

words, relieve the upper springs 26 of any opposing pressure. This mechanism therefore restores the machine to what is termed the standard type of flat work ironer or one in 5 which the ironing rolls bear upon the work with their own weight plus any pressure of the upper springs 26.

Arranged within pressure bar 14 and between thrust collars 25 and 27 is suitable pressure and padding indicating mechanism. Said mechanism comprises a link 48 pivotally mounted in ear 29 of collar 27 and carrying at its lower end a pin 49 pivotally connected to a link 50, the lower end of which is pivoted 15 on a screw 51 in an arm 52 of a lever pivoted at 53, Fig. 6, to the eye 30 of collar 25. Said lever is provided with an offset arm 54 extending to one side and pivoted to a screw 55 secured to the inner wall of the pressure bar 20 14. Referring to Figs. 3 and 6, it is obvious that when the fixed collar 25 with its ear 30 moves downwardly, said lever will rock in a clockwise direction about the pivot 55, Fig. 3, but when the collar 25 remains stationary 25 and the collar 27 is moved downwardly in compressing the upper spring 26, the toggles formed by the links 48 and 50 will break to the right, as shown in Fig. 3. This toggle effect is utilized for indicating the degree of pressure 30 exerted by the upper spring upon the ironing roll, as will more fully appear. The said rocking movement of the lever is utilized through the downward movement of the collar 25 to vary the padding indication accompanying 35 the change in the degrees in pressure as the ironing roll gets accordingly smaller due to the compacting of the padding 13. The pressure indication is accomplished by means of a sliding bar 56 arranged to slide in 40 a suitable guide 57 in the housing 17, said bar being held in place by an indication plate 58 secured upon the side face of guide member 57 by screws 59 as shown in Figs. 3 and 5. This plate 58 carries the legends "High", 45 "Normal" and "Low" arranged from right to left. The inner end of said bar is T-shaped and provided with a slot 60 to receive the pin 49, while the other end of the bar is provided with an indicating point 61 cooperating with 50 graduations on a pressure indicating plate 62 secured at the end of the housing 17. It is clear that as the hand wheel 21 is manipulated and the pressure of the spring 26 varied, the bar 56 will indicate the pressure being applied 55 through the roll to the work.

The padding indicator comprises a finger 63 which is an angular extension of the lever arm 52 and extends up in front of the plate 58 so that it may move over the face thereof and 60 cooperate with the legends "High", "Normal" and "Low" to indicate the condition of the padding.

In machines of the standard flat work ironer type, the pressure bars 14 are moved 65 up and down to carry the ironing rolls into

and out of cooperation with the bed by suitable mechanism, the type herein shown for each bar comprising rods 64 and 65, each provided with an integral strap 66 engaging an eccentric 67 arranged on shafts 68 and 69. 70 These shafts are provided with worm wheels 70 driven by worms 71 upon a shaft 72 suitably geared to a hand wheel 73 or any other source of power. This mechanism, while old and well known, properly forms a part of the 75 organization of this case in that when the eccentrics are downward, as shown in Fig. 1, and the ironing rolls are in the critical or best ironing condition, as will later appear, the bars 14 rest upon the stops 3. In fact, it is important that the bars should rest upon these stops before the eccentrics have exerted their entire downward movement, as will clearly appear from the description of the 80 operation of the floating roll principle involved in this mechanism and the original adjustment of the ironing rolls in setting up the machine.

In order to appreciate the present mechanism, it is important to have a clear understanding of the peculiarities of padding. It has already been stated that the ironing rolls are padded by wrapping a layer of felt or other similar material about the roll in a plurality of convolutions and covering this 90 inner padding structure with an outer cover cloth also wound upon the roll. When a roll is freshly padded, it is obviously much larger than when it has been run for a short length of time, because the rolls are driven in a direction that causes the padding to wrap itself thereupon. After a short period of time, depending upon the pressure on the padding, the thickness of the padding will 95 change but slightly throughout a relatively long continuous period of use because there is an inherent tendency in the padding to unwrap somewhat similar to the action of a clock spring and when the traction between the ironing roll and the ironing bed resulting from the pressure exerted upon the roll is equal to or less than the wrapping tendency, then the roll will tend to slip without further appreciable wrapping. This condition is what may be termed the critical or 100 best condition of the ironing roll. At this particular time it is relatively soft and pliable and permits the materials to imbed themselves in it, thereby doing away with rough-dry spots along the edges of the thickened portion and producing a desirable finish upon the goods. In the presence of heat, moisture and pressure, however, the roll continues to wrap or pack slightly and become 105 hard, or in other words, to pass from this desirable "Normal" condition to the undesirable "Low" padding condition. It is also clear 110 that as the padding compacts and reduces in thickness, the pressure drops accordingly. The inter-connection of the padding indica- 115 120 125 130

tor and the pressure indicator therefore serves to produce the indications with the relative change present.

With the foregoing in mind, the machine is set up and operated in the following manner:

If the machine be a new one, the rolls are left unpadded and a shim 74 is inserted between the projections 5 and 10, Fig. 3, so that the bearing is supported at a definite height. This position is the one which the bearings of each roll should assume when the padding is normal or when it has been compacted to the best condition. When the shim is in place, the pressure is removed from the upper spring 26 by unscrewing the pressure screw 19. The adjusting nut 34 in web 23 of the pressure bar 14 is then adjusted until the padding indicator arm 63 stands at "Normal," as shown in Fig. 3, the operator being sure, however, that the lowering mechanism for the pressure bar 14 is in a position such that the bar engages the stops or supports 3. When in this position, the lower springs 33 are so supported by members 3 that the ironing roll, if normally padded will be in contact with the ironing face of the bed 7 at substantially zero or no pressure. The operator then adjusts the pressure screw 19 until the desired pressure is brought to bear upon the ironing roll through the upper springs 26. When this is done the bars 14 may be raised and the rolls padded with new padding. If the machine is already in use, the shim 74 need not be used unless the nut 34 has moved out of adjustment or the lower springs 33 have lost their tension. After the adjustments have been made, the shims 74 are removed. In this position, the padded roll is in "Normal" condition, that is, will bear upon the bed with the desired ironing pressure, exerted by the upper springs 26 and without the added weight of the ironing roll. If the padding is renewed, the same adjustment is retained, but the indicator will stand at "High" padding when under pressure and will quickly move down to "Normal" over a period of a few hours, whereas, it will remain at "Normal," and move from that point to "Low" after many days or weeks. By reason of the inter-connection of the padding indicator and the pressure indicator, the pressure will drop as the padding is compacted and the indicators will serve to indicate this condition, so that it may be readily corrected by adjustment of the hand screws 19.

What I claim is:

1. In an ironing machine, a bed, a padded ironing roll, a supporting member, yielding means carried thereby for supporting the roll, whereby the roll and said supporting member are relatively adjustable, means on said supporting member for producing variable yielding pressure of the roll toward the bed, and means governed by the relative ad-

justment between the roll and said supporting member for indicating the amount of compression of the padding.

2. In an ironing machine, a bed, a padded ironing roll, an adjustable support for said roll, means on said support for producing variable yielding pressure of the roll toward the bed, and means actuated by said pressure producing means for indicating the pressure upon the work. 70 75

3. In an ironing machine, a bed, a padded ironing roll, means for exerting ironing pressure upon said roll to cause it to engage the bed with ironing pressure, a pressure indicator, a padding condition indicator, and means whereby a change in either the padding or pressure conditions of said roll produces a change in the indications of both of said indicators. 80

4. In an ironing machine, a bed, a padded ironing roll, means for exerting ironing pressure upon said roll to cause it to engage the bed with ironing pressure, a pressure indicator, a padding condition indicator, and means connecting said indicators whereby a change in the padding condition of said roll produces a change in the indication of pressure effective upon the work. 85 90

5. In an ironing machine, a bed, a plurality of padded ironing rolls, opposed yielding devices for supporting said rolls to cause them to float with the desired ironing pressure upon the work, means for indicating the pressure and the padding conditions of said rolls, and means connecting said indicating devices whereby a change in the padding condition produces a change in the indication of the pressure condition of said rolls. 95 100

6. In an ironing machine, a bed, a padded ironing roll, means for supporting said roll in co-operative relation with the bed, means for adjusting said roll supporting means with respect to the bed and for establishing a pre-determined definite relation therebetween, means carried by said roll supporting means for yieldingly supporting the roll in said relation at zero pressure upon the bed when without pressure from above, means for exerting ironing pressure upon said roll, and means arranged when said roll supporting means is in said relation to at all times indicate the padding condition of said roll. 110 115

7. In an ironing machine, a bed, a padded ironing roll, means for supporting said roll in co-operative relation with the bed, means for adjusting said roll-supporting means with respect to the bed and for establishing a pre-determined definite relation therebetween, means carried by said roll supporting means for yieldingly supporting the roll in said relation at zero pressure upon the bed when without pressure from above, means for exerting ironing pressure upon said roll, and means connected to said roll and said roll supporting means and said pressure exerting 120 125 130

means for indicating the pressure upon and the padding condition of said ironing roll.

8. In an ironing machine, a bed, a plurality of ironing rolls, supporting means for all of said rolls movable as a unit toward and from the bed, means for adjusting said roll supporting means with respect to the bed and for establishing a predetermined relation therebetween, means carried by said roll supporting means for yieldingly supporting said rolls at zero pressure upon the bed when without pressure from above, adjustable means for each roll for exerting variable ironing pressure upon it and separate pressure indicating mechanisms, one for each of said rolls, each of said mechanisms being operatively connected to its roll and its adjustable pressure producing means, whereby each operates independently of the others and is unaffected by adjustment of said supporting means.

9. In an ironing machine, a bed, an ironing roll, means for supporting said roll in co-operative relation with the bed, means for positioning said roll supporting means in a predetermined relation with respect to the bed, means carried by said roll supporting means for yieldingly supporting the roll at zero pressure upon the bed when without pressure from above, means for exerting ironing pressure upon said roll, and means for rendering ineffective said yielding supporting means.

10. In an ironing machine, a bed, a plurality of padded ironing rolls, supporting means for all of said rolls and movable as a unit toward and from the bed, means for positioning said roll supporting means in a predetermined relation with respect to the bed, means carried by said roll supporting means for yieldingly sustaining said rolls and relieving the work of the weight of the rolls, means for exerting ironing pressure upon said rolls, and a single means for rendering ineffective said yielding sustaining means for said rolls.

11. In an ironing machine, a bed, an ironing roll, means for supporting and guiding said roll for a floating roll type of machine wherein the ironing roll is supported between opposed yielding pressures, and means for converting said machine into a type wherein the pressure opposing the ironing pressure is relieved.

12. In an ironing machine, a bed, a padded ironing roll, and means operatively associated with said roll for indicating its padded condition.

13. An ironing machine, comprising a bed, a padded ironing roll, a movable member adjustable toward and from said bed and yieldably supporting said roll, and means operatively associated with both said roll and member for at all times indicating the padding condition thereof.

14. An ironing machine, comprising an ironing bed, an ironing roll cooperating with

said bed, supporting means for said roll, means for moving said roll supporting means toward and from said bed, means for determining and fixing a definite position of said roll supporting means relative to the bed in which position the roll on said supporting means contacts with the bed but with no pressure thereon when all the ironing pressure hereafter referred to is removed, and means effective upon said roll for producing ironing pressure between said roll and the bed.

15. An ironing machine, comprising an ironing bed, an ironing roll, cooperating with said bed, yielding supporting means for said roll, means for moving said roll supporting means toward and from said bed, means for determining and fixing a definite position of said roll supporting means relative to the bed in which position the roll on said supporting means contacts with the bed but with no pressure thereon when all the ironing pressure hereafter referred to is removed, and means effective upon said roll for producing ironing pressure between said roll and the bed.

16. An ironing machine, comprising an ironing bed, an ironing roll cooperating with said bed, means for moving said roll toward and from said bed, supporting means for said roll carried by and movable with said roll moving means, means for determining and fixing a definite position of said roll supporting means relative to the bed in which position the roll on said supporting means contacts with the bed but with no pressure thereon when all the ironing pressure hereafter referred to is removed, and means effective upon said roll for producing ironing pressure between said roll and the bed.

17. An ironing machine comprising an ironing bed, an ironing roll cooperating with said bed, means for moving said roll toward and from said bed, supporting means for said roll movable with said roll moving means and adjustable relative thereto, means for determining and fixing a definite position of said roll supporting means relative to the bed in which position the roll on said supporting means contacts with the bed but with no pressure thereon when all the ironing pressure hereafter referred to is removed, and means effective upon said roll for producing ironing pressure between said roll and the bed.

18. An ironing machine, comprising an ironing bed, a plurality of ironing rolls cooperating with said bed, a single member common to all of said rolls and adapted when actuated to move said rolls toward and from said bed, means for actuating said member, supporting means for each of said rolls movable with said member, means for determining and fixing a definite position of said roll supporting means relative to the bed in which position the rolls on said supporting means

contact with the bed but with no pressure thereon when all the ironing pressure hereafter referred to is removed, and means effective upon each roll for producing ironing pressure between said roll and the bed, said series of pressure producing means being individually adjustable.

19. An ironing machine, comprising a frame an ironing bed carried thereby, an ironing roll cooperating with said bed, means for moving said roll toward and from said bed, supporting means for said roll movable with said roll moving means, means forming a rigid part of said frame for determining and fixing a definite position of said supporting means relative to the bed in which position the roll on said supporting means contacts with the bed but with no pressure thereon when all of the ironing pressure hereafter referred to is removed, and means effective upon said roll for producing ironing pressure between said roll and the bed.

20. An ironing machine, comprising an ironing bed, an ironing roll cooperating with said bed, a rod connected to said roll and extending to one side of its axis, and a pair of yielding means effective upon said rod, one of said yielding means being adapted to support at least a part of the weight of said roll and the other yielding means being adapted to produce ironing pressure between said bed and said roll.

21. In an ironing machine, an ironing bed, an ironing roll cooperating with said bed, a rod connected to said roll and extending to one side of its axis, and near and far yielding means effective upon said rod, said near yielding means being adapted to support at least a part of the weight of said roll and said far yielding means being adapted to produce ironing pressure between said bed and said roll.

22. In an ironing machine, an ironing bed, an ironing roll cooperating with said bed, a rod connected to said roll and extending to one side of its axis, a pair of yielding means surrounding said rod, and abutment means carried by said rod and arranged between said yielding means and adapted to be engaged by both, one of said yielding means being adapted to support at least a part of the weight of said roll and the other yielding means being adapted to produce ironing pressure between said bed and said roll.

23. In an ironing machine, an ironing bed, an ironing roll cooperating with said bed, a rod connected to said roll and extending to

one side of its axis, a pair of yielding means surrounding said rod, one of said yielding means being adapted to support at least a part of the weight of said roll and the other yielding means being adapted to produce ironing pressure between said bed and said roll, abutment means carried by said rod and arranged between said yielding means and adapted to be engaged by the adjacent ends thereof, and two additional abutment means adjustably associated with said rod and adapted to be engaged by the other ends of said yielding means.

24. In an ironing machine, an ironing bed, an ironing roll cooperating with said bed, a member adapted when actuated to move said roll toward and from said bed, means for actuating said member, a rod secured to said roll and extending to one side of its axis, a pair of yielding means surrounding said rod, one of said yielding means being adapted to support at least a part of the weight of said roll and the other yielding means being adapted to produce ironing pressure between said bed and said roll, abutment means carried by said rod and arranged between said pair of yielding means and adapted to be engaged by the adjacent ends thereof, and two additional abutment means adjustably carried by said roll moving member and associated with said rod and adapted to be engaged by the other ends of said pair of yielding means.

25. In an ironing machine, an ironing bed, an ironing roll cooperating therewith, yielding means adapted to support at least a part of the weight of said roll, means for producing ironing pressure between said roll and said bed, and means for rendering said yielding means ineffective.

26. In an ironing machine, an ironing bed, an ironing roll cooperating therewith, means for moving said roll toward and from said bed, yielding means movable with said roll moving means and adapted to support at least a part of the weight of said roll, and means for rendering said yielding means ineffective.

27. In an ironing machine, an ironing bed, a plurality of ironing rolls cooperating therewith, means for each roll adapted to support at least a part of the weight of said roll, means for producing ironing pressure between said rolls and said bed, and a single means for rendering said roll supporting means ineffective.

In testimonys whereof I hereby affix my signature.

HOWARD C. CURTISS.
